RADIORECEIVER

Lysle G. Tatro, Decorah, Iowa, assignor to H. B. Montgomery, Decorah, Iowa

Application March 29, 1930. Serial No. 440,076

6 Claims. (Cl. 250—27)

This invention relates to radio receiving sets and has among its aims to provide an improved receiving set utilizing a battery supplied direct current system or the like, not only for current supply but also as a novel "filament loop" for intercepting radio frequency waves and transferring the same to the receiver through the filament of the radio frequency amplifier.

In the present specification an illustrative embodiment of my invention is described with reference to a "farm-power" system of the 32-volt storage battery type, but throughout the present specification, the terms "farm-power" and "farm-lighting" are to be understood as illustrative terms or catch phrases intended to designate equivalent systems capable of employment as an untuned "filament loop" in accordance with my invention, including, for example, direct current sources comprising primary or secondary batteries and commercial sources of such capability.

Particular objects and advantages of the invention will be apparent to those skilled in the art from the following description of the preferred embodiments of the several features of my invention shown in the accompanying drawings to illustrate the same.

Referring to the drawings constituting a part of this specification:

Fig. 1 is a diagrammatic representation of a complete radio receiving system embodying the several coordinated features of my invention;

Fig. 2 is a rear elevation of a filament potential limiting and heat dissipating unit illustrative of one embodiment of this feature of my invention; and

Fig. 3 is a sectional plan view of the same taken at line 3—3 of Fig. 2.

Referring to Figs. 1^a and 1^b of the drawings, the receiving system therein shown comprises a specially adapted receiver circuit preferably employing three stages of radio-frequency amplification, (advantageously of the screen-grid direct current heated thermionic amplifier tube type), a thermionic detector to convert the amplified radio-frequency current into audio-frequency current and an amplifier for the audio-frequency current, preferably comprising, in addition to one or more intermediate audio-frequency amplifiers, a last stage audio-frequency amplifier of the "push pull" type.

Throughout the showing of Figs. 1^a and 1^b the circuit is entirely independent of any earthing connection, the several grounded points throughout the diagram indicating electrical connections to shielding with which the set is provided.

Referring to Fig. 1^a, the circuit which I prefer to use, modified according to my invention, comprises a first radio-frequency coil 10 connected at its opposite ends to the grid 11 of the first

thermionic amplifier 12, and to the receiver shielding, as at 13. The plate 14 of amplifier 12 connects through primary winding 15 of the radio-frequency transformer 16 with the lead 17, which connects with the "B amplifier" post of the "B" and "C" power unit hereinafter described. The negative side of the "B" source of this unit is connected to the shielding of the set and the output circuit of the first thermionic amplifier is completed by way of the connection 18, connecting the shielding with the negative side of the filament 19 by way of the variable resistor 20, the function of which is described hereinafter. The input circuit of the first thermionic amplifier 12, is also completed by this shield connection 18.

The secondary 21 of the radio-frequency transformer 16, tuned by the variable capacity 22 is connected to the grid and negative side of the filament of the second thermionic amplifier 23, the output circuit of which includes the primary 24 of radio-frequency transformer 25. The input circuit of the third radio-frequency amplifier 26 includes the secondary 27 of the radio-frequency transformer 25, and is tuned by means of the variable capacity 28, and the output circuit of this radio-frequency amplifier 26 includes the primary 29 of radio-frequency transformer 30.

The three screen grids of the three radio-frequency amplifiers 12, 23 and 26 are interconnected without suppression and connected to a positive source of potential, conveniently the "B" and "C" power unit, by means of lead 32.

The secondary 33 of radio-frequency transformer 30 is included in the input circuit of the thermionic detector 34, provided with the usual grid leak 35 and condenser 36, and is tuned by means of a variable capacity 37.

The variable tuning capacities 22, 28, and 37 are preferably interconnected for "gang-tuning" as indicated by the dotted lines 38.

The output circuit of the detector 34 includes a radio-frequency choke coil 39, the primary 40 of the audio-frequency transformer 41, and by connection with lead 32, connects through the detector section of my "B" and "C" power unit with the shielding of the set, the by-pass condenser 42 bridging the radio-frequency choke coil 39, the audio-frequency transformer primary 40 and the detector "B" power supply.

The "C" power supply, for negatively biasing the grid of the amplifier tube 44, which is connected between the "C" negative lead 52 and the set shielding, and the secondary 43 of the audio-frequency transformer 41, are included in the input circuit of the first audio-frequency amplifier 44 (see Fig. 1^b) and this input circuit is also preferably bridged by a phonograph pick-up jack 45. The output of the audio-frequency amplifier includes the resistance unit 46, and is

- coupled in any suitable known manner, as by the Clough system of coupling shown at 47, to the input side of the push-pull amplifier stage, which includes the thermionic amplifiers 48 and 48'.
 5 The output of this push-pull amplifier stage is connected to a suitable loud speaker, preferably of the dynamic type and having a field winding designed for operation at the ordinary direct-current farm-power system voltage, usually about
 10 thirty-two volts.

As shown in Fig. 1^a, suitable condensers 49, 50 and 51 are inserted across the detector and amplifier "B" power circuits and the "C" power circuit, as is well known in the art, by connecting them between the set shielding and the leads 32, 17, and 52, respectively.

As thus far described the system, while novel in some respects, in general represents merely a modification of known circuits, and the particularly novel aspects of my invention will now be described.

The disclosed embodiment of my improved system is particularly devised and adapted to be operated from battery supplied direct current systems such as the usual direct current farm power systems, generally comprising a thirty-two volt storage battery and charging plant and from several hundred to several thousand feet of farm power lines, usually comprising an ungrounded system. I will first describe those parts of my invention which relate to the lighting of the filaments of the thermionic tubes from the farm-power system.

It has been proposed to connect the several tube filaments of a radio receiver in series and operate them from a relatively high voltage current source, but this type of connection is not satisfactory either from a technical or a practical standpoint. With such connection the burning out of a single tube filament prevents any of the tubes from lighting, thus making it difficult to determine which tube has burned out, and the control of volume and the several filament currents becomes technically involved.

45 It has also been proposed to connect all the filaments in parallel and use a single resistance in the high voltage line to reduce the voltage thereof to the operating voltage of the several tubes. This proposal is impracticable because
 50 the burning out of one tube results in increasing the voltage impressed upon the other tube filaments and frequently causes burning out of the whole set of tubes. Furthermore, the control of volume with such an arrangement cannot be accomplished in a wholly satisfactory manner, and the concentrated heat of the series resistor frequently damages the condensers and other parts of the set or cabinet in which it is mounted.

According to my invention, I provide for the
 60 reduction of line voltage to filament lighting voltage with perfect volume control and without undue concentration of heat by providing a multiple-resistor unit, an illustrative embodiment of which is shown in detail in Figs. 2 and 65 3 and generally indicated in Fig. 1 by the number 53.

Referring to Figs. 2 and 3, this multiple-resistor unit is preferably made up of a plurality of resistance units (indicated in Fig. 1 as 54) 70 mounted between two channels 55 of highly heat conductive material such as aluminum. The resistance units are of the externally wire wound insulator tube type, and the assembly of the units and channels is effected by means such as bolts or rivets 56 passed through the channels

55 and insulating tubes 57. One resistor is provided for each tube in the set, and an additional resistor is preferably provided for the dial light 58 (see Fig. 1). One end of each of the resistances is connected to a bus bar 59 or other common lead in any suitable manner as by clamps 60; and if bare wire resistances, as shown, are used, the effective resistance interposed in each of the filament circuits may be varied by setting the movable clamps 61 at different positions along the resistance units. These clamps 61 will be set so that when the storage battery of the farm-power system of given voltage rating is fully charged or at its highest voltage, the full operating voltage for the particular tube used will be impressed thereon, and it will be obvious that the maximum of voltage thus allowed to be supplied to the filament terminals will be permanently determined and limited, for a given installation, insuring long tube life and satisfactory operation.

The provisions thus made for varying the effective resistances, and thus the filament currents, are advantageous not only to allow a standard unit to be used on farm lighting systems of different voltages, but also to provide for changing the filament voltage to enable the use of thermionic tubes utilizing various filament voltages. Of course, if neither of these advantages is desired fixed resistance units may be substituted for the variable units described above.

The multiple-resistor unit is of large area and may be permanently mounted either directly upon the chassis of the receiver, or with a layer of heat insulating material, or spacing washers, interposed. The attachment will thus become a permanent part of the receiver and as the several resistors each give forth only a small amount of heat, and are quite widely separated, 110 danger of excessive heat localization, which might injure the insulation or the cabinet finish, is avoided.

The bus-connection 59, as shown in Fig. 1^b is adapted to be connected to the positive side 115 of the farm current system 70 through one blade of a plug 62, preferably of the polarized type, and the negative sides of the filament circuits of the detector and audio-frequency amplifier tubes are grounded to the set shielding, from which the 120 filament circuit is completed as hereinafter described. To provide for adequate and simple volume control the negative sides of the filaments of the three radio-frequency amplifying tubes are connected together and the common lead 63 125 therefrom is carried through the variable volume controlling resistance 20, Fig. 1, the opposite side of which is grounded to the shielding of the set by way of lead 18.

According to my invention the other circuits 130 for supplying operating potential to the thermionic tubes; namely, the negative "C" and positive "B" power leads 52, 17 and 32, and the common positive "C" and negative "B" lead 64, are preferably carried in a single cable provided at 135 its end with a connector strip 65 adapted to be attached to a combined "B" and "C" power unit only in such manner as will properly connect to the set, all the "B" and "C" power connections simultaneously, as described in my U. S. Patent No. 1,901,272, granted March 14, 1933.

The lead 66 from the negative side of the farm-power circuit, and the lead 64 from the negative side of the "B" power supply and the positive side of the "C" power supply are iso- 140 145

lated from the receiver by the off and on switch 67, and accordingly when this switch 67 is in "off" or open position, all current supplying circuits of my system are broken, including the circuit for energizing the field coil of the dynamic speaker, the positive lead 68 of which is connected to the positive side of the farm-power circuit inside the receiver and the negative lead 69 of which is grounded to the set shield, thus necessitating closure of the switch 67 to complete the negative side of its circuit.

In case of excessive arcing in the switch 67 due to the inductive effect of the field coil of the speaker, the switch 67 may be bridged by a suitable condenser as is well known in the art.

As above noted the "farm power" system illustrative of systems to which my invention is particularly applicable usually comprises a storage battery and charger therefor and from several hundred to several thousand feet of power lines, and is usually ungrounded.

According to my invention this entire system is used as a "filament loop", or counterpoise connected in the filament circuit of the receiver, and the resulting great pick-up of radio-frequency current enables my receiver to be operated with very little drain of "B" current, so that dry-cell battery units may be satisfactorily used to supply the "B" current for the receiver.

Referring to Fig. 1, the common filament current leads 59 and 66, as above noted, are connected by means of the polarized plug 62 with the positive and negative lines, respectively, of the "farm-power" system generally indicated by the numeral 70, and it will be noted that the entire system 70 is thus connected directly across these common filament lines, and that this system is in no other way coupled to the receiver. As a result of thus forming a "filament loop" from the common filament leads 59 and 66, through the battery of the "farm power" system, the high capacity of which inherently provides for passage of radio-frequency energy therethrough with substantially no diminution, an untuned loop or counterpoise is formed, and the switching on or off of any lamp 71 has no appreciable effect upon the transmission of radio waves picked up thereby to the receiver.

I have found that under all conditions, using this "filament loop" according to my invention, when the "farm power" system is ungrounded, extremely great pick up of radio waves is effected even without the use of any antenna or earth connection, particularly when the point of connection of the plug 62 to the system is considerably removed from the battery and charger unit thereof. In some instances, particularly when the connection of the plug 62 to the system is quite proximate to the battery and charger unit, i. e., within a few feet thereof, I have found it advantageous to supplement the pick-up of the filament loop by connecting to the post 72 (Fig. 1a) in the grid circuit of the first radio-frequency tube 12, a short antenna or an earthing lead. If the "farm-power" system is of the ungrounded or unearthed type, as is usually the case, it seems immaterial whether the post 72 be connected to an aerial or to earth, but if the system is earthed, either by design or through accident, I find that somewhat better results are obtained by the use of a short antenna connected to post 72 rather than an earthing lead.

Thus, while my receiving system is primarily designed to employ an unearthing "farm power" system or the like as the filament loop, with or

without a short antenna or an earthing lead connected to the post 72, in its broad aspects my invention includes the use in my receiving system of a grounded filament loop with or without the use of a short antenna connected to post 72, and while I prefer to utilize the filament loop alone, locating the connection of the receiver thereto at a considerable distance from the battery and charger unit, as shown, in its broad aspects my invention is not limited in this respect.

As above noted, the screen grids of the three radio-frequency amplifiers are, according to my invention, interconnected without suppression, so that the full effect and advantage of the screen-grid system can be utilized. I am enabled to avoid suppression of the screen-grid currents because of the fact that the great radio wave interceptive power of the "farm-power" wiring employed as a filament loop enables me to operate the several amplifying tubes of my receiver at a greatly reduced plate potential without sacrifice of sensitivity, and in addition to these advantages enables me to reduce the plate current drain of the entire receiver to the order of 9 milliamperes of current (using 84 volts maximum plate potential) thus producing a seven tube screen grid receiver, which can be successfully operated over long periods of time on a single set of dry cell "B" batteries, an advantage which has never heretofore been accomplished so far as I am aware.

My receiving system may be successfully operated using ordinary "B" batteries and the ordinary "C" battery for grid biasing, but I prefer, when using "B" and "C" batteries, to employ a special "B" and "C" power unit adapted to be connected directly to the connector strip 65, as shown in Fig. 1b, and fully disclosed in my above mentioned Patent No. 1,901,272, as the use of such unit insures that before failure of the unit substantially all the effective life of substantially all the cells will have been made use of, in contradistinction to the ordinary tapped "B" unit in which the cells drawn upon by the detector and amplifier tubes become exhausted long before the entire life of the cells drawn upon by the amplifier tubes alone has been served. Moreover, my unit construction insures replacement of all the "B" and "C" battery supplies at the same time, which is essential for the best results with the receiver.

It is clear from the above description that the ultimate result of the several improvements comprised in my invention is the production of a greatly improved radio receiver capable of long and very efficient service where city power circuits are not available, and one in which every detail is so arranged as to present no technical problems to the lay user as to how certain connections should be made and whether or not certain of the "B" or "C" power supplies should be replaced or retained.

Having described what I consider to be the best embodiments of my invention, I wish it to be distinctly understood, however, that the specific descriptions above are not intended to be limiting, but are intended to be merely illustrative and that I claim as my invention all equivalents of the novel combinations and features of my preferred embodiment.

I claim:

1. A "filament loop" radio receiving system, said system comprising a source of direct current, power conductors leading therefrom, a radio receiver embodying thermionic vacuum tubes, con-

- nections from said power conductors to the filaments of said vacuum tubes for energizing said filaments from said source of direct current, said filaments, connections, conductors and source of 5 direct current forming a closed loop coupled to said receiver essentially by way of the direct inclusion of said filaments, as distinguished from separate capacity coupling, said system having its radio-frequency wave intercepting means 10 constituted substantially entirely by said filament-including closed loop.
2. A "filament loop" radio receiving system, said system comprising a source of direct current, power conductors leading therefrom, a 15 shielded radio receiver embodying thermionic vacuum tubes with the filaments thereof connected at one side to the receiver shielding, a connection from one of said power conductors to said receiver shielding, connections from the other 20 power conductor to the other sides of said filaments for energizing the same from said source of direct current, said filaments, connections, conductors and source of direct current forming a closed loop coupled to said receiver essentially 25 by way of the direct inclusion of said filaments, as distinguished from separate capacity coupling, the radio-frequency wave intercepting means of the system being constituted essentially by said filament-including closed loop.
3. A "filament-loop" radio receiving system, said system comprising a radio receiver embodying a plurality of thermionic vacuum tubes comprising thermionic radio-frequency amplifying, thermionic detecting, and thermionic audio-frequency amplifying elements, an external source of current and power conductors leading therefrom, means including separate resistors individually connecting the filaments of said vacuum tubes at one side thereof to one of said power 30 conductors, means connecting the other terminals of said detecting and audio-frequency amplifying tube filaments directly to the other of said power conductors, and volume controlling means connecting the other terminals of said 35 radio-frequency amplifying tube filaments to said other power conductor, said filaments, connecting means, conductors and current source forming a closed loop coupled to said receiver essentially by way of the direct inclusion of said 40 filaments, as distinguished from separate capacity coupling, said system having its radio-frequency wave intercepting means constituted essentially by said filament-including closed loop.
4. A "filament-loop" radio receiving system, 45 said system including a receiver comprising a thermionic vacuum tube having a filament, an external source of current and power conductors leading therefrom, and means connecting said filament to said power conductors to be energized from said current source, said filament, connecting means, conductors and current source forming a closed loop coupled to said receiver essentially by way of the direct inclusion of said 50 filament, as distinguished from separate capacity 55 coupling, the radio-frequency energy intercepting means of said system being constituted essentially by said filament-including closed loop.
5. In a radio receiving system, a shielded radio receiver embodying a detector, radio-frequency, and audio-frequency vacuum tubes having filaments, one side of which is connected to said shielding, and plates connected to the positive "B" potential leads, at least one of said audio-frequency tubes having its grid return connected to a source of negative "C" biasing potential, a pair of farm lighting conductors having a potential difference materially greater than the rated filament voltage of any one of said filaments, an individual voltage dropping resistance connected in series with the other end of each one of said filaments and connected to one of said pair of farm lighting conductors, each of said individual resistances being of such value as to reduce the maximum farm lighting conductor potential difference to the maximum rated filament potential of the filament to which it is connected, a separate variable resistance interposed in the connections from said radio-frequency tubes to said shielding, a loud speaker embodying a field circuit 60 with leads extending therefrom, said field circuit leads connected respectively to the above mentioned one of said pair of farm lighting conductors and to said shielding; the other of said farm lighting conductors, together with the negative "B" potential lead and the positive "C" potential lead being connected through a single switch the opening of which effects the breaking of the filament, "B", "C" and loud speaker field circuits.
6. In a radio receiving system, a shielded radio receiver embodying a detector radio-frequency, and audio-frequency vacuum tubes having filaments, one side of which is connected to said shielding, and plates connected to the positive "B" potential leads, a pair of farm lighting conductors having a potential difference materially greater than the rated filament voltage of any one of said filaments, an individual voltage dropping resistance connected in series with the other end of each one of said filaments and connected to one of said pair of farm lighting conductors, each of said individual resistances being of such value as to reduce the maximum farm lighting conductor potential difference to the maximum rated filament potential of the filament to which it is connected, a separate variable resistance interposed in the connections from said radio-frequency tubes to said shielding, a loud speaker embodying a field circuit with leads extending therefrom, said field circuit leads connected respectively to the above mentioned one of said pair of farm lighting conductors and to said shielding; the other of said farm lighting conductors, together with the negative "B" potential lead being connected through a single switch the opening of which effects the breaking of the filament, "B" and loud speaker field circuits.
